UNITED STATES PATENT OFFICE.

JAMES C. MOCK, OF DETROIT, MICHIGAN, ASSIGNOR TO THE UNION SWITCH AND SIGNAL COMPANY, OF SWISSVALE, PENNSYLVANIA, A CORPORATION OF PENNSYLVANIA.

AUTOMATIC STOP FOR RAILWAY SAFETY APPLIANCES.

No. 918,887.

Specification of Letters Patent.

Patented April 20, 1909.

Application filed February 28, 1907. Serial No. 359,754.

To all whom it may concern:

Be it known that I, JAMES C. MOCK, a citizen of the United States, residing at Detroit, in the county of Wayne, State of Michigan, have invented certain new and useful Improvements in Automatic Stops for Railway Safety Appliances; and I do declare the following to be a full, clear, and exact description of the invention, such as will enable others skilled in the art to which it appertains to make and use the same, reference being had to the accompanying drawings, and to the figures of reference marked thereon, which form a part of this specification.

15. This invention relates to automatic stops for railway safety appliances adapted for use in connection with the usual signals at block stations or other points along the track, and consists in the association and arrangement 20 of parts hereinafter more fully set forth and claimed.

The objects of the invention are to provide simple and efficient means for automatically applying the brakes or operating other stopping mechanism on a train where the engineer or motorman fails to see or to obey a signal, and allows the train to pass said signal without coming to a stop, or without placing the train under control as the case may be.

30. A further object is to provide means for allowing a slow movement of a train past danger signals, or a reverse movement at slow speed without operating the automatic stop; and a further object is to provide 35 means for actuating the stopping mechanism operated in accordance with the speed at which the train or car may be running.

The above objects are attained by the mechanism illustrated in the accompanying 40 drawings, in which:

Figure 1 is an end elevation of a locomotive with the pilot removed and the track in transverse section, showing a contacting-device at the side of the track and one embodiment of the automatic controlling device for the stopping mechanism mounted on the engine. Fig. 2 is a side elevation of the forward end of a locomotive upon which my controlling device for the stopping mechanism is located, parts of said device being in section, as well as the mechanically actuated trip or contactor located adjacent to the track. Fig. 3 is a horizontal section through the valve which controls the discharge of air

from the train pipe, showing said valve in the closed position. Fig. 4 is a similar view showing said valve in the open position.

In the application of my invention I may employ various physical embodiments thereof, but in all cases the operation of the device will depend upon the speed of the train, whereby an engine-man may be allowed to pass a danger signal at slow speed or slowly run the train by said signal in a reverse direction without making an application of the brakes through the operation of the automatic stopping device.

One embodiment of my invention as shown herein in connection with the ordinary air brake system, consists in mounting upon the end of the axle 1 a beveled gear 2 which meshes with a like gear 3 on the lower end of the vertical shaft 4. The shaft 4 is journaled in suitable bearings 5 formed in the arms of a bracket 6 bolted to the truck frame of the locomotive, or to the truck frame of a car, as the case may be.

Pivoted at 7 to the upper end of the shaft 4 are the upper arms 8 of the ball governor 9, the lower arms 10 of said governor being pivotally connected at 11 to the collar 12 loosely mounted on the shaft 4 and adapted to slide vertically. Also loosely mounted on the shaft 4 and adapted for vertical movement thereon is a weight 13 which is supported by the collar 12.

A lever 14 is fulcrumed at 15 to an ear of the bracket 6, one end of said lever being bifurcated and journaled at 16 to a ring 17 lying freely in a peripheral channel in the collar 12. The other end of said lever is pivoted at 18 to the upper end of a rod 19 having at its lower end a ball 20.

Formed in the body of the bracket 6 is an air passage way 21 which communicates at its upper end with the train pipe 22 common to all air brake systems. The lower end of the passage way 21 extends through a fitting 23 on the bracket 6 and terminates in an exhaust port 24. Seated in said fitting 23 and controlling said port is a plug cock valve 25. Depending from the bracket 6 is an extension arm 26 in the lower end of which a square shaft 27 is supported to slide vertically. Secured to the lower end of the shaft 27 and projecting horizontally is an arm 28. The shaft 27 at its upper end passes freely through the valve 25 which is provided with

a square central aperture to receive said shaft. The upper end of the shaft 27 above said valve is provided with a socket fitting 29 that receives the ball 20 on the lower end of the rod 19. By this arrangement, it will be evident that a movement of the lever 14 on its fulcrum will cause shaft 27 to slide vertically, and it will also be evident that a rotation of said shaft will turn the valve 25 in its seat to open or close the port 24. The rotary motion of said shaft is not imparted to the rod 19, owing to the ball and socket connection between said parts.

Traversing one side of the valve 25 is a channel 30 which when in the open position, as shown in Fig. 4, connects the channel 21 with the port 24 and permits the air to escape from the train pipe, effecting an application of the brakes, as will be well understood in the art. The closed position of the valve, which is its normal position, as shown in Fig. 3, maintains the air in the train pipe.

Located at the side of the track is a suitable housing 31 preferably supported by the ties, as shown. Seated in said housing is a vertically movable contacting pin 32 having a flaring cap 33 on its upper end which embraces the boss 34 of the housing surrounding said pin, to exclude snow and water from said housing. Located in the housing 31 to reciprocate longitudinally is a slide plate 35 having a longitudinal slot 36 with an inclined portion 37. The lower end of the contacting pin 32 is bifurcated and straddles the plate 35, its bifurcated ends being joined by a transverse pin 38 which passes through said slot. Connected to one end of the slotted plate is a rod 39 which leads to a semaphore or other signaling apparatus, not shown, the arrangement being such that the operation of the signaling device will actuate the plate 35 in the following manner:—When the signal is set at danger, the plate 35 will be moved longitudinally to cause the pin 38 to ride up the inclined portion 37 of the slot in said plate, thereby projecting the contactor from the housing, as shown by dotted lines in Fig. 1. A reverse movement of said plate will restore said contactor to its normal position.

The operation of the device as herein shown, is as follows:—The setting of the signal at danger will raise the contacting pin to the dotted position shown in Fig. 1. Should the engine-man obey the signal and reduce the speed of his train so as to place it under immediate control, the train will be allowed to slowly pass the signal at danger without operating the automatic stopping device. Should the engine-man however fail to see the signal or to obey it, and should the train upon reaching the signal be running at regular or high speed, shaft 4 through its connection with the axle will be revolved so rapidly as to cause the balls of the governor, by cen-

trifugal force, to swing outwardly and raise the collar 12, as shown by dotted lines in Figs. 1 and 2, at the same time lifting the weight 13. The upward movement of the collar 12 will actuate the lever 14 to depress the outer end thereof and carry downwardly the shaft 27 so as to extend the arm 28 on the lower end thereof sufficient to cause it to engage the upper end of the contacting pin, whereby said shaft will be turned to rotate the valve 25 and open the port 24, permitting the air to escape from the train pipe and making an application of the brakes. As the speed of the train is reduced the balls of the governor will fall and the weight 13 will restore the parts to their normal position.

It will be evident that with the train moving at a slow rate of speed, the centrifugal force of the governors will not be sufficient to operate the lever 14 and depress the arm 18 of the shaft 27 such distance as to cause it to engage the contacting pin. By this arrangement a train is enabled to run past the danger signal when under control and is also enabled to back when required for switching or for other purposes, without actuating the automatic stopping device, an arrangement of material importance where the traffic is heavy, as the ordinary movement of the train is not interfered with, and delays incident to the undesired application of the brakes on long trains, are obviated.

Having thus fully set forth my invention, what I claim as new and desire to secure by Letters Patent, is:—

1. A train stopping device comprising the stopping mechanism, a contacting device adjacent to the track, apparatus operatively associated with the contacting device and with the stopping mechanism, and actuated according to the speed of the train, to cause an operation of the stopping mechanism, when the train in passing the contacting device exceeds a predetermined speed.

2. In a train stopping device, the combination with the stopping mechanism, of a movable arm controlling the stopping mechanism, a contactor adjacent to the track normally out of the plane of said arm, and apparatus operatively associated with said arm and actuated according to the speed of the train to move said arm and cause it to engage said contactor.

3. In a train stopping device, the combination with a train pipe valve, of a movable arm to open said valve, a contactor near the track adapted to actuate said arm; and means operated through the movement of the train in passing said contactor at a predetermined speed for projecting said arm to cause it to engage said contactor.

4. In a train stopping device, the combination with a train pipe valve, of a movable arm to open said valve a vertically movable contactor adapted to engage and ac-

- tuate said arm, means operated according to the speed of the train for projecting said arm to cause it to engage the contactor, and means for actuating said contactor.
5. In a train stopping device, the combination with a train pipe valve, of a vertically movable arm to open said valve, a track device adapted to actuate said arm, and means associated with said vertically movable arm, and operated according to the speed of the train for depressing said arm to cause it to engage said track device when the passing train exceeds a predetermined speed.
6. In a train stopping device, the combination with the brake applying mechanism, of a movable part controlling the brake applying mechanism, an operative arm connected with said movable part, a track device to engage said arm, and means driven from the axle for carrying said arm into position to engage said track device.
7. In a train stopping device, the combination with a train pipe valve, of a vertically movable shaft associated with said valve, a track device for actuating said shaft to turn said valve, a rotary shaft driven from the axle, a ball governor on said shaft, and means connected with said governor for raising and lowering said shaft.
8. A train stopping device, comprising the stopping mechanism, a movable part controlling the stopping mechanism, a track device, and means driven from the axle for placing said movable part in position to engage said track device.
9. A train stopping device, comprising the stopping mechanism, a movable part controlling the stopping mechanism, a track device, and means actuated according to the speed of the train for placing said movable part in position to engage said track device.
10. A train stopping device, comprising the stopping mechanism, a track device, a movable member controlling the stopping mechanism, apparatus operatively associated with said movable member and actuated according to the speed of the train to move said member into operative relation with the track device.
11. In apparatus for controlling the speed of the train, a normally closed control valve, trip actuated mechanism on the train for opening said valve, and a governor controlled by the speed of the train for controlling the operation of the trip actuated mechanism; substantially as described.
12. In apparatus for controlling the speed of trains, a normally closed control valve, a trip actuated mechanism for opening said valve, and a centrifugal device operated by the speed of the train and controlling the operation of the trip actuated mechanism; substantially as described.
13. In train control apparatus, a train carried trip arm, and means controlled by the speed of the train for moving said arm into and out of operative position; substantially as described.
14. In train control apparatus, a trip device carried by the train, valve mechanism operated thereby, and a controlling device arranged to move the trip into and out of operative position, and itself controlled by the speed of the train; substantially as described.
15. In apparatus for train control, a brake-operating valve, a trip device for operating the same, and a speed governor actuated by the train and controlling the operation of the trip-device; substantially as described.
16. The combination with a trip located in the trackway, a brake applying mechanism carried by a car, and means also carried by the car which will cause the brake applying mechanism to apply the brakes when the train is traveling at one speed and which will prevent the brakes being applied when the train is traveling at slow speed.
17. The combination with a train stopping apparatus carried by a car, a trip located in the trackway and having an operative position, and means carried by the car which will cause the train stopping apparatus to act when the car is traveling at one speed and which will prevent the device from acting when the train is traveling at a different speed.
18. The combination with a train stopping apparatus carried by a car, a trip located in the trackway and having an operative position, and means carried by the car controlled by the speed of the car for causing an operation of the train stopping apparatus by the trip in its operative position when the car is moving faster than a predetermined speed.
19. The combination with a train stopping apparatus carried by a car and adapted to assume an operative or an inoperative position according to the speed of the car, and a trip located in the trackway and having an operative position to engage the apparatus carried by the car when in its operative position.
20. In combination, means located in or alongside the trackway for causing an operation of a stopping mechanism carried by a car traveling along the trackway only when the car is traveling at more than a predetermined speed past said means, the stopping mechanism carried by the car, means wholly carried by the car for causing an operation of the stopping mechanism by the means located in the trackway if the car is traveling at more than the predetermined speed, and a governor carried by the car and driven from a wheel or axle of the car for preventing an operation of the stopping means of the car, independently of the means located in the trackway, when the car is traveling at less than the predetermined speed.

21. In combination, means located in or alongside the trackway for causing an operation of a stopping mechanism carried by a car traveling along the trackway only when the car is traveling at more than a predetermined speed past said means, the stopping mechanism carried by the car, means wholly carried by the car and operatively connected with the governor and comprising a part by the car for causing an operation of said stopping mechanism by said means, and a governor also carried by the car, driven from a wheel or axle of the car and operatively connected with said means, said governor being adapted when the car is traveling at a slow speed past the means in the trackway to prevent an operation of the stopping mechanism thereby. 40
- 10 which is movable to accord with the variations of the governor for preventing an operation of the stopping mechanism by the means located in the trackway when the car passes said means if the car is traveling at less than 50 the predetermined speed. 15
22. In combination, means located in or alongside the trackway for causing an operation of a stopping mechanism carried by a car traveling along the trackway only when the car is traveling at more than a predetermined speed past said means, the stopping mechanism carried by the car, a governor carried by the car and driven from a wheel or axle of the car, means carried by the car and operatively connected with the governor comprising a part movable into and out of position for engagement with the means in the trackway, according to the speed of the car for controlling the operation of the stopping mechanism. 25
23. In combination, means located in or alongside the trackway for causing an operation of a stopping mechanism carried by a car traveling along the trackway when the car is traveling at more than a predetermined speed past said means, the stopping mechanism carried by the car, means carried by the car for causing an operation of said stopping mechanism by said means, and a governor also carried by the car, driven from a wheel or axle of the car and operatively connected with said means, said governor being adapted when the car is traveling at a slow speed past the means in the trackway to prevent an operation of the stopping mechanism thereby. 45
24. In combination, a device located in or alongside the trackway for causing an operation of a stopping mechanism carried by a car traveling along the trackway only when the car is traveling at more than a predetermined speed past said device, the stopping mechanism carried by the car, means carried by the car for causing an operation of said stopping means when engaged by said device, said means comprising a movable part, and a governor carried by the car and driven from a wheel or axle of the car for moving said part into or out of position to be engaged by said device according to the speed of the car. 55
25. The combination with a trip on the trackway of a movable brake controlling member on the car, and a governor carried by the car, controlled by the speed of the car, operating to put the brake control member into and out of engaging position with the trip. 60
- In testimony whereof, I sign this specification in the presence of two witnesses.
